UNITED STATES PATENT OFFICE.

JOEL E. BIDWELL, OF KALAMAZOO, MICHIGAN.

DESIGN FOR A RADIATOR.

SPECIFICATION forming part of Design No. 22,493, dated May 30, 1893.

Application filed March 1, 1893. Serial No. 464,258. Term of patent 7 years.

To all whom it may concern:

Be it known that I, JOEL E. BIDWELL, a citizen of the United States, residing at the city of Kalamazoo, in the county of Kalamazoo and State of Michigan, have invented a certain new and useful Design for Radiators, of which the following is a specification.

The accompanying drawing represents a perspective view of one of my newly designed radiators.

The radiator loops I are connected together and each provided with an imitation of a hop vine bearing its peculiar leaves *a*, and fruit *b*, arranged to run from or over the top of each loop I part way down each side and terminating in a cluster of hops *b*, *b*, at the end. On the lower portions of each loop I, on each side is a similar decoration composed of a hop vine combined with its leaves *a*, and hops *b*, terminating in a cluster of hops *b*, *b*, at the top. A plain portion D, is left between the decorations at the top and the decorations at the bottom of the loops.

The design gives the radiator the appear-

ance of being trimmed at the top and bottom 25 with vines of the hop. The hops, leaves and vines are so varied that the rows of hops and leaves show very distinctly across the loops. This has the effect to break the sameness of appearance from the top to the bottom of the 30 radiator. The number of the loops I in my radiator may be varied, or the height changed, as neither is essential to my design, the essential thing being a radiator design in which the loops of the radiator have the appearance 35 of being decorated at both the top and the bottom with the vine of the hop as shown in the accompanying drawing.

What I claim is—

The design for a radiator as herein described and shown.

In witness whereof I have hereunto set my hand and seal in the presence of two witnesses.

JOEL E. BIDWELL. [L. S.]
